United States Patent Office.

G. MAYER, OF SULLIVAN, ILLINOIS.

Letters Patent No. 96,456, dated November 2, 1869.

IMPROVED TRUSS.

The Schedule referred to in these Letters Patent and making part of the same.

To all whom it may concern:

Be it known that I, G. MAYER, of Sullivan, in the county of Moultrie, and State of Illinois, have invented a new and improved Truss; and I do hereby declare that the following is a full, clear, and exact description thereof, which will enable others skilled in the art to make and use the same, reference being had to the accompanying drawing, forming part of this specification.

This invention relates to improvements in trusses for hernia, and has for its object to provide a simple, cheap, and effective construction of the same, and in adjustable arrangement of the pads, to be either worn single or double, and adapted for males or females; and

It consists in arranging oblong pads in triangular pieces, that are sustained by two straps from the belt, secured upon the opposite corners of the pieces, in connection with a strap that unites the pieces together.

The drawing represents a front view of my improved truss applied to a human subject.

A is the waistband, to be applied to the waist by buckling behind at B, and may be provided with suspenders C or not, as preferred.

D represents short straps, pendant from the front of the waistband, in two pairs, in suitable position at each side of the centre of the front, for the connection of the broad strap E, to which the pads F are connected.

G represents two similar short straps, pendant from the waistband behind, for the connection of the sin-

gle straps H, which are continuations of the broad straps E, and pass between the thighs, as shown in dotted lines.

The upper parts of the broad pad-holding straps E are provided with two short and narrow straps, corresponding to the straps D, and buckled to them so as to be let out or taken up, as required, to bring the pads higher or lower, as may be required, according to the location of the rupture, the straps H being correspondingly adjusted.

The wide straps holding the pads may be connected together by a short strap, I, to draw the pads away from the thighs when worn by females, and required to be very low, but made removable for adaptation to males.

In this improved truss, no steel or other metallic plates or springs are used, which it is highly desirable to avoid, as they sometimes chafe and injure the wearer.

Having thus described my invention, I claim as new, and desire to secure by Letters Patent—

The arrangement of waistband A, front straps D, back straps G, pad straps E, and detachable strap I, all constructed and shaped with respect to each other, in the manner described.

The above specification of my invention signed by me, this 9th day of August, 1869.

G. MAYER.
